CLOCK

Benjamin Levy, Hewlett, N.Y., assignor to United Metal Goods Mfg. Co., Inc., Brooklyn, N.Y., a corporation of New York

Filed Oct. 24, 1965, Ser. No. 87,931

Term of patent 7 years

(Cl. D42—7)

FIG. 1 is a front perspective view of a clock showing my new design; and

FIG. 2 is a rear elevational view thereof.

The essential features of the design are shown in full lines.

I claim:

The ornamental design for a clock, substantially as shown and described.
